[57] CLAIM

The ornamental design for a container, as shown and described.

DESCRIPTION

FIG. 1 is an exploded perspective view of the right side of the container showing my new design;
FIG. 2 is a top plan view thereof;
FIG. 3 is a right side elevational view thereof; the opposite side being a mirror image thereof;
FIG. 4 is a front elevational view thereof;
FIG. 5 is a bottom plan view thereof;
FIG. 6 is a rear elevational view thereof;
FIG. 7 is a sectional elevational view thereof; taken along line 7—7 of FIG. 6; and,
FIG. 8 is a right side perspective view thereof.
